BRACKET LAMP OR SIMILAR ARTICLE

Frank Skupien, 5443 S. Wolcott, Chicago, Ill. 60609

Filed May 20, 1971, Ser. No. 145,598

Term of patent 14 years

Int. Cl. D26—05

U.S. Cl. D48—4

Fig. 1

Fig. 2

FIG. 1 is a perspective view of a bracket lamp or similar article embodying my new design; and

FIG. 2 is a top plan view of the bracket lamp.

The rear surface of the bracket lamp is plain and the other surfaces not shown are substantially the same as those of the corresponding surfaces shown.

I claim:

The ornamental design for a bracket lamp or similar article, as shown.
